[57] CLAIM

The ornamental design for a knee pad for babies, toddlers and small children, as shown and described.

DESCRIPTION

FIG. 1 is a front elevation view of a knee pad for babies, toddlers and small children showing my new design; FIG. 2 is a rear elevation view thereof; and, FIG. 3 is a top plan view thereof.

The shading representing woven fabric material shown in all views is understood to repeat throughout the indicated areas. The broken lines in FIGS. 1 and 2 represents conventional stitching.

FIG. 1.

FIG. 2.

FIG. 3.
